Primary Examiner—A. Hugo Word*Assistant Examiner*—Doris V. Coles*Attorney, Agent, or Firm*—Keith Schoff**[57] CLAIM**

The ornamental design for a universal long-gun sling, as shown and described.

DESCRIPTION

FIG. 1 is a perspective view of a universal long-gun sling showing my new design;

FIG. 2 is a top plan view, the bottom plan view being a

mirror image; and,

FIG. 3 is a side elevational view, the opposite side being essentially a mirror image.

FIG. 1

FIG. 3

FIG. 2
